UNITED STATES PATENT OFFICE.

ROBERT SPENCER, OF NEW YORK, N. Y.

IMPROVEMENT IN LADIES' RIDING-SADDLES.

Specification forming part of Letters Patent No. 16,556, dated February 3, 1857.

To all whom it may concern:

Be it known that I, ROBERT SPENCER, of the city, county, and State of New York, have invented new and useful Improvements in Ladies' Riding-Saddles; and I do hereby declare that the following is a full, clear, and exact description thereof, reference being had to the accompanying drawings, making part of this specification, in which—

Figure 1 is a plan view of the saddle-tree; Fig. 2, a side elevation; Fig. 3, a cross vertical section taken at the line A a of Fig. 1; and Figs. 4 and 5 represent a plan and cross-section of a modification of my said improvements.

The same letters indicate like parts in all the figures.

As ladies' saddles have heretofore been constructed they are in many respects unsafe and uncomfortable to the rider and injurious to the horse; and the object of my said invention is to avoid the defects heretofore experienced; and the first part of my invention relates to a change in the form and position of the pommel or head, whereby the position of the rider is rendered more easy and safe, while at the same time the horse's withers are left free and clear of all tendency to chafe; and the second part of my said invention relates to a mode of adjusting the position of the main or short horn relatively to the seat and pommel, whereby it can be adapted to persons of different sizes; and the third part of my said invention relates to the manner of arranging the stirrup-leather, whereby the weight of the rider is balanced on the horse, and thereby rendered more safe than heretofore, in combination with what are known as "Mexican bars," whereby I am enabled to dispense with the points heretofore employed to embrace the sides of the horse, and to substitute in lieu thereof in a lady's saddle the well-known Mexican bars, which merely embrace the horse's withers, and which have no tendency to chafe or to impede the free action of the horse.

In the accompanying drawings, *a a* represent the two bars of the tree, which are formed with the front part *b* in the manner of the well-known Mexican saddle, each properly fitted to the hollow of the horse on each side of the withers, and the pommel *c*, which unites the two bars in front, instead of being placed directly across and at the extreme forward

end of the bars, as heretofore, and which requires it to be very much elevated to clear the horse's withers, is thrown back and in a diagonal position, whereby it can be considerably depressed without danger of injuring the horse. The upper surface of this pommel extends over to the right or off side of the saddle by a gentle upward slope to a sufficient distance to give the required extent of bearing-surface for the outside of the thigh, which rests in the head or horn, and the right or off side may be of the form represented in Figs. 1, 2, and 3, or extended to form an outer resting-horn, as at *s*, Figs. 4 and 5, or of any other form to suit the fancy of the constructor. By this means the thigh is brought down very nearly to the level of the seat, so that the rider will sit with much more ease and comfort and have a better control than when the thigh is elevated, as it must be on saddles constructed as heretofore.

The short or main horn *d* may be attached in the usual manner and permanently to and project from the head or bar on the left or near side of the pommel, as represented in Figs. 4 and 5, or, what I prefer, it may be attached as represented in Figs. 1, 2, and 3, by a screw in the end tapped into a metal plate *e*, provided with three (more or less) holes, into either of which it can be inserted, so that it can be shifted at pleasure from one position to another, higher or lower, forward or back, to suit the length and diameter of thigh of the rider, as the ease and comfort of the rider greatly depend upon a proper position of the horn relatively to the pommel and rear part of the seat, which should always be adjusted to the size and form of the rider.

If desired, a leaping-horn *f* may be attached either to the riding-horn or to the bar of the tree, this making no part of my invention.

As the weight of the rider preponderates on the left or near side by reason of the two legs being on that side and the left foot in the stirrup, the saddle, as heretofore constructed, always has a tendency to turn or drag down on the left or near side of the horse, and the only way in which this tendency has been heretofore resisted is by the use of two points at the forward part of the saddle, one on each side, and embracing the horse just back of the shoulders. This is known to be injurious to

the horse, as he is bound where he is required to be free when in proper action, and as that part of his body necessarily has much motion, there is a constant chafing of the skin, which is necessarily injurious, and a still more serious objection to the old construction is that the rider depends entirely on the strength of the girth for safety, because if the girth breaks the preponderance of the weight of the rider on the left or stirrup side will necessarily make the saddle slide off on that side. To avoid these objections, I attach the stirrup-leather *g* by a staple *h*, or other suitable means, to a projection *i* on the right or off side of the pommel, and after passing under the horse it is brought up on the left or near side and through a suitable loop or opening *j* in the double stirrup-bar plate *e*, and thence down, so that when the foot of the rider is in the stirrup *k* the weight will act on both sides of the saddle, and by increasing the length of the projection *i*, to which the stirrup-leather is attached, the leverage on the right or off side can be made so much greater than that on the left side as to balance the weight of the rider, and thereby avoid all the defects above pointed out, and by this means I am enabled to dispense with the points heretofore employed to embrace the sides of the horse, and to substitute what is known as the "Mexican bars," which fit into the cavities each side of the withers without chafing the horse.

Having thus described my said invention and the various modes in which I have contemplated the application thereof, I wish it to be distinctly understood that I do not limit my claim of invention to such special modes of application, as other equivalent modes may be substituted.

What I claim as my invention, and desire to secure by Letters Patent, is—

1. Placing the pommel or head back of the front edge of the bars and in a diagonal position, substantially as described, whereby I am enabled to depress it to give ease of position to the rider without interfering with the horse's withers, as described.

2. Connecting the near or short horn with the tree by a screw on the end fitted to a series of holes, so that its position relatively to the seat and pommel may be shifted at pleasure to suit the rider, substantially as described.

3. The arrangement of the stirrup-leather, substantially as described, in combination with what are known as the "Mexican bars" *a b*, substantially as above described, whereby I am enabled to make a secure lady's saddle without the use of the points heretofore employed for embracing the sides of the horse, as set forth.

ROBT. SPENCER.
